(57) **CLAIM**

The ornamental design for a memory card, as shown and described.

DESCRIPTION

FIG. 1 is a perspective view of a memory card, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the memory card with a cover shown in broken lines not forming a part of the invention claimed.

1 Claim, 5 Drawing Sheets

FIG. 1

FIG.2

FIG.3

FIG.4
